[73] Assignee: KKH, Inc., Calif.

[57] CLAIM

[] Term: 14 Years

The ornamental design for an ornamental child's pillow in the fanciful form of a dinosaur, as shown and described.

[21] Appl. No.: 12,616

DESCRIPTION

[22] Filed: Sep. 7, 1993

FIG. 1 is a perspective view of the pillow taken from above the left front corner;

[52] U.S. Cl. D6/598; D6/601;

FIG. 2 is a top plan view thereof;

D21/148

FIG. 3 is a perspective view thereof taken from below the right rear corner; and,

[58] Field of Search D6/595-598;

FIG. 4 is a bottom plan view thereof.

297/250.1, 219.12; D3/234, 235, 236, 238;

The stippled shading represents conventional fabric and is understood to extend uniformly throughout the areas represented.

D21/148
